UNITED STATES PATENT OFFICE.

THOMAS H. McAULIFFE, OF LYNN, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,103,979.

Specification of Letters Patent. Patented July 21, 1914.

Application filed May 23, 1912. Serial No. 699,189.

To all whom it may concern:

Be it known that I, THOMAS H. McAULIFFE, a citizen of the United States, residing at Lynn, in the county of Essex and State of 5 Massachusetts, have invented certain Improvements in Lasting-Machines, of which the following description, in connection with the accompanying drawings, is a specification, like reference characters on the 10 drawings indicating like parts in the several figures.

This invention relates to lasting machines and more particularly to lasting machines of the type described in United States Letters Patent No. 584,744, dated June 15, 1897. Lasting machines of the type described in said prior Letters Patent and commonly known as "hand method lasting machines" have usually employed a 15 reciprocating presser or wiper for stretching and laying down the edge or margin of the upper around the toe to force the upper into the angle of union between the feather-edge and lip of the inner 20 sole, herein sometimes designated the "sole", said terms being intended to include the single sole of a turn shoe as well as the inner sole of a welt or other shoe having inner and outer soles. By this means the upper 25 is worked into proper position to be secured by temporary tacks or by a wire binder and at the same time the plaiting action of the pincers is materially assisted. The reciprocating presser in its forward 30 movement is, however, apt to strike and mar the edge of the upper and to break and mutilate the feather-edge of the sole. Frequently, too, the action of the reciprocating presser in thus creasing the upper into the 35 angle between the feather-edge and lip of the sole results in tearing the leather, especially if it be thin or tender leather such for example as is frequently the case with patent or enameled leather. Moreover, when 40 the wiper is retracted the stretched portion of the upper is very likely to slip back more or less. To correct these various defects and to obviate these disadvantages several constructions have been devised. It has been 45 proposed to employ a circular disk wiper with an unbroken and smooth periphery and arranged to have a continuous rolling engagement with the upper. It has also been 50 proposed to make use of a rotatable disk

shaped wiper with its periphery scalloped 55 to form peripheral fingers, these fingers being better adapted to engage and hold the stock firmly and to work it into the desired position than the smooth periphery of the former wiper. In the use of this scalloped 60 wiper heretofore it has however been arranged to be actuated intermittently between successive plaiting movements of the pincers and it has been found in practice that although this form of wiper is much 65 more efficient in bending down and holding the upper materials in place than either of the wipers before mentioned, nevertheless its efficiency is limited because, like the reciprocating presser, its operation is inter- 70 mittent.

I have discovered that improved results can be obtained by actuating the wiper to bend and break down into place the stiff upper materials in advance of the folding over 75 and laying of the plaits by the pincers and also for further rubbing the upper in lasted position after each plait is formed and laid. By the additional action of the wiper on the stock thus provided in accordance with this 80 invention the work of the pincers is facilitated and also the upper after being left by the pincers is further treated to form it permanently in its lasted position. Moreover, around the toe of the shoe which is the portion 85 for which the wipers are particularly intended the bulky upper materials stand out stiffly from the last and a greater and more constant pressure can be advantageously employed to crease the stock into 90 the angle between the feather-edge and lip of the sole than can be given by the intermittently operated presser.

Accordingly with a view to improving the construction and operation of the above-mentioned forms of wipers, the present invention contemplates the provision of means for continuously operating the wiper when it is in work engaging position. The invention is shown as embodied in a machine 95 of the type shown in said Letters Patent and as applied to a rotatable disk wiper with peripheral fingers, of the type above mentioned, although the invention is of course not limited either to use in connection with this particular form of wiper or to use in this particular type of machine.

In the embodiment of the invention here-

in shown and hereinafter described in detail, the wiper is actuated through connections with a gear on the main cam shaft of the machine. It would be obviously undesirable to have the wiper continuously rotated at all times when the machine is running regardless of whether or not it is desired that the wiper be used and hence a convenient and efficient arrangement is provided for causing adjustment of the wiper to and from operative position automatically to connect and disconnect the wiper from its actuating mechanism.

A feature of the present invention consists in the fact that the wiper by reason of its continuous rotation in engagement with the upper operates particularly successfully to place the toe binder in binding relation to the upper. Furthermore, the continuously rotating wiper by constantly engaging the upper to strain and stretch it into place relieves the pincers of a large part of the upper stretching and consequently cooperates most effectively with the pincers thus facilitating greatly their work.

It should also be noticed as a further feature that the present invention as preferably embodied is peculiarly adapted for holding the stock firmly to prevent any slipping back or unfolding of the plaited and stretched portions of the upper.

These and other features and advantages of the present invention will be apparent from the following detailed description read in connection with the drawings which show one illustrative embodiment of the invention.

Referring to the drawings:—Figure 1 is a side view in elevation of a portion of a lasting machine of the type referred to with the present invention applied thereto; Fig. 2 is a top plan view of the rotatable wiper and its associated parts including the mechanism for actuating the wiper; Fig. 3 is a detail of the actuating mechanism for the wiper; Fig. 4 is a detail of the mechanism for disconnecting the wiper from its actuating mechanism; and Fig. 5 is a section taken on the line 5—5 of Fig. 2.

The machine to which by way of illustration this invention is described as being applied, comprises a column A which supports a framework or head B on which are mounted the various operating parts of the machine and in which is journaled the main cam shaft D (Fig. 1). The cam shaft D has upon it the cams and gears which give the proper motions to the several mechanisms for operating the various lasting devices.

The pincers 14, 16 are mounted at the front of the machine and are operated by suitable mechanisms to descend and grip the edge of the upper, then to rise and stretch the upper and then to move down-

wardly and forwardly toward the middle portion of the innersole to lay the stretched portion of the upper down in position to receive a fastening tack. Tacks are supplied by a double raceway 18 adjustable to feed different sized tacks to the tack-carrier or tack-block 20, the tack-block 20 also serving as a presser to hold the stretched and laid upper in tack receiving position for the insertion of the tacks after the grippers have retreated preparatory to again stretching and over laying another portion of the upper.

In addition to the pincers movements above referred to, it is necessary at times, particularly in lasting around the toe, and sometimes at other points, to give the pincers other movements to fold or plait the upper in order to dispose of the fullness of upper materials at those points. In order to thus move the pincers to plait the upper at the toe, suitable mechanism operated from a cam on the main shaft is provided, this mechanism including adjustable means for rendering the plaiting means operative or inoperative as desired through movement of a knee lever 22 which turns a rockshaft 24, movement of the rockshaft 24 in turn through suitable connections operating a sliding block 26 for starting, stopping and controlling the lateral and turning or plaiting movements of the pincers.

For a full disclosure of the complete machine to which the present invention is described as being applied and for a complete description of the construction and operation of the above mentioned mechanisms and parts, reference should be had to said prior Letters Patent No. 584,744. Reference should also be had to said patent for all other details of construction and of operation of parts not fully described herein since except as hereinafter indicated and described in detail the construction and operation may most conveniently be as described and explained in said prior patent.

As above stated it is necessary in lasting around the toe and sometimes at other points to employ a wiper or presser to bend down the stiff outstanding upper materials and to crowd the upper down into the angle of union between the feather-edge and lip of the inner-sole. For this purpose, preferably a rotatable wiper or presser 28 is employed, the wiper 28 being substantially like that above referred to. The wiper 28 is located in a plane below the intermediate plate B' of the machine and slightly below the track-carrier 20 (Fig. 1). The wiper 28 has a hub 30 by which it is rotatably mounted in a plate 32 which is in turn secured as by bolts or the like to the underside of the pivotally mounted wiper carrier 34. The carrier 34 is cut away at 35 to overlap and partially cover the wiper 28.

The carrier 34 is pivoted on a boss 38 on the intermediate plate B' (Fig. 1) being held on said boss by a cap plate 40 and a screw 42.

In order that the wiper may be adjusted 5 into and out of operative position the carrier 34 is provided with an arm 36, the arm 36 having gear teeth meshing with similar teeth on an arm 39 of the rock shaft 24 above mentioned. From this it will be seen 10 that whenever the knee lever 22 is moved to actuate the rock shaft 24 for throwing the plaiting means into and out of operation as above stated and as fully described in said prior patent, the wiper carrier 34 will at 15 the same time be automatically adjusted to swing the carrier 34 and the wiper 28 about their axis either into the operative position shown in Fig. 2 for lasting the toe or reversely and backwardly out of operative position 20 when the heel and sides are being lasted and it is not desired to use the wiper. Co-operating stops may conveniently be placed at 41 and at 43 to limit the outward movement of the carrier 34 and a spring pin 44 25 mounted in the rocker arm 38 engages shallow recesses 46 in the under face of the intermediate plate B' to retain the presser in adjusted positions.

The presser 34 has its periphery scalloped 30 to form fingers 48, these fingers being slightly cut away or beveled on the under side and being as before stated peculiarly adapted for engaging and creasing the upper into the angle 49 between the feather 35 edge and lip of the inner sole (Fig. 2) as well as for permitting the driving of the tacks between them, if tacks are employed to secure temporarily the upper in lasted position. In lasting Goodyear or welt shoes 40 it is, however, commonly the practice to secure the upper in lasted position around the toe by means of a wire toe binder *w* (Fig. 2), the wire being supplied from a reel conveniently located on the machine and being 45 guided by an arm 50, the guide 50 being attached to the plate 32 so as to be moved to and from operative position simultaneously with the adjustments of the wiper 28. The wiper 28 in addition to wiping the upper into the angle 49 also operates as a presser and by engagement of the vertical edges of the fingers 48 with the wire *w*, the wire *w* is pressed downwardly and inwardly into the said angle 49 as clearly shown in 50 Fig. 2. Moreover the beveled formation of the fingers 48 permits them to slightly overlie the wire and thus to press it into position positively and effectively, as shown in Fig. 5.

The operating mechanism for rotating the 60 wiper 28 is actuated by a spiral gear 52 on the main shaft D. A similar gear 54, shown in dotted lines in Fig. 1 and in full lines in Fig. 2, is arranged to engage the gear 52. The gear 54 is fixed on a vertical shaft 56 (Fig. 3) and the shaft 56 carries at its lower 65 end a fixed bevel gear 58. One arm of a bracket hanger 60 embraces the shaft 56 just above the gear 58 while the other and depending arm of the hanger 60 serves as a journal bearing for one end of a horizontal 70 shaft 62. A bevel gear 64 with its teeth intermeshing with the teeth of the gear 58 is loose upon the shaft 62 and a clutch device is provided as will be explained below for causing the shafts 56 and 62 to rotate together when desired. Secured to its other end the horizontal shaft 62 carries a bevel gear 66 which meshes with a companion gear 68 fixed to the under side of a spur gear 70. The spur gear 70 meshes with a pinion 72 80 fixed to the under side of the wiper 28 and through which the hub 30 of the wiper 28 passes. Hence it will be seen that whenever the shaft 62 is rotated by means of the above described gearing the wiper 28 will likewise and simultaneously be rotated.

It will be observed that whenever the machine is running, the shaft 56 which is operated through connection with the gear 52 on the main shaft D will be continuously 90 rotated and if the shafts 56 and 62 were arranged to be always rotated together, it would follow that the wiper 28 would be continuously rotated whenever the machine is in motion. To prevent the unnecessary 95 wear of machine parts which would thus be occasioned, as above stated, the gear 64 is loose on the shaft 62 and a clutch device is provided for causing the shaft 62 to be rotated with shaft 56 when desired. This 100 clutch device preferably comprises the toothed member 74 fixed with relation to the gear 64 and the correspondingly toothed companion clutch member 76 which, as shown in Fig. 4, has a pin and slot connection with the shaft 62 by which it is permitted a certain amount of lengthwise movement along shaft 62 but is prevented from turning on the said shaft. To cause the clutch members 74 and 76 to be brought 110 into clutching engagement with each other the shaft 62 is mounted for longitudinal or lengthwise movement in its bearing so that movement of shaft 62 to the right (Fig. 3) will bring the clutch members into the disengaged position shown in Fig. 4 while movement of shaft 62 reversely to the left again will bring the clutch members into engagement as shown in Fig. 3. As shown 115 in Fig. 2 these connections of the wiper 120 with and disconnections from its actuating mechanism are preferably made to occur simultaneously with and by reason of the adjustments of the wiper 28 to and from the operative position of Fig. 2 by reason 125 of the fact that whenever the wiper is swung from the position of Fig. 2 backwardly to its retreated and inoperative position the pinion 72 on the wiper 28 will necessarily through engagement with the 130

gear 70 on the sliding rod 62 push the shaft 62 backward thus forcing the clutch members apart into the disengaged position shown in Fig. 4 while movement of wiper 28 to the front again will cause shaft 62 to be pulled forwardly until the clutch members 74 and 76 are again in clutch engagement.

To insure that when the members 74 and 76 are brought into engagement the teeth of each will register in the opposite recesses of the other a fairly stiff spring 78 is coiled within the clutch member 76 around the shaft 62 and is seated against a washer 80, the spring 78 tending to press the member 76 forwardly and toward the member 74 so that if the teeth of the two clutch members fail properly to register, as soon as the clutch member 74 is turned enough to permit, the teeth of the clutch member 76 will be pressed forward into engagement with the corresponding recesses in the member 74.

From the above description it will be apparent that by reason of the continuous rotation of the wiper 28 while it is in operative position, taken in connection with its scalloped and beveled formation, not only will it act positively and powerfully to crowd the upper inwardly into the angle 49 before the pincers seize it but also during the interval between the release of one portion of the upper by the pincers and the seizure of a fresh portion the wiper will actively operate to gather the fresh portion 35 of the upper inwardly toward lasted position and to rub down upon the shoe bottom the portion released by the pincers. The wiper thus acts in a two-fold manner as a supplementary lasting means. As the pincers move laterally in the direction to carry the upper in under the wiper, or into the angle between the wiper and the body of the shoe, the wiper "bites" and assists to gather inwardly the plaited upper while the 45 scalloped projections of the wiper, as it is continuously rotated act by impact to drive the upper against the lip or shoulder of the innersole. In this manner the upper is set in lasted position by rapidly repeated blows 50 of gradually increasing closeness of contact directed horizontally against the stock. Furthermore, the difficulty previously experienced in distributing the fullness of the upper evenly either side of the center of the 55 toe so as to prevent unsightly bunches and folds is almost entirely obviated by the use of my invention. By its constant rotation in engagement with the binder *w*, the wiper moreover will press the stiff wire into place 60 in a manner heretofore unknown. At the same time, convenient and practicable means are provided for automatically adjusting the wiper to and from operative position with the throwing in and out of the plaiting 65 means and for simultaneously connecting

and disconnecting the wiper with and from its operating mechanism.

Having described in detail an illustrative embodiment of my invention, what I claim as new and desire to secure by Letters Patent of the United States is:—

1. A lasting machine having, in combination, upper stretching means, a member for forcing the upper into the angle between the feather-edge and lip of the sole and mechanism for imparting continuous uninterrupted operative movement to said member. 75

2. A lasting machine having, in combination, means for stretching the upper, a member constantly in engagement with the edge 80 of the upper to crease the upper into the angle of union between the feather-edge and lip of the sole and mechanism for imparting continuous uninterrupted operative movement to said member. 85

3. A lasting machine having, in combination, upper stretching means, a member for crowding the stretched upper into the angle of union between the feather-edge and lip of the inner sole, means for adjusting said 90 member to and from operative position and means for imparting continuous uninterrupted operative movement to said member when it is in operative position. 95

4. In a lasting machine, the combination 100 of a rotatable wiper for forcing the upper into the angle of union between the feather-edge and lip of the sole and mechanism for effecting continuous uninterrupted rotation of said wiper, substantially as described. 100

5. In a lasting machine, the combination 105 with upper stretching instrumentalities, of a wiper substantially as described and movable into and from operative position, operating mechanism for imparting continuous uninterrupted rotary movement to the wiper when operatively connected with the wiper, and connections from the wiper to said operating mechanism arranged to effect operative connection between the wiper and said 110 operating mechanism when the wiper is moved into operative position. 110

6. A lasting machine having, in combination, upper stretching and manipulating means, a rotatable wiper, operating mechanism therefor including means for continuously rotating said wiper, and means for disconnecting the wiper from said wiper rotating means. 115

7. A lasting machine having, in combination, a rotatable wiper, means for adjusting the wiper to and from operative position, means for continuously rotating the wiper while it is in operative position and means operated by adjustment of the wiper 120 into inoperative position for disconnecting the wiper from said operating mechanism. 125

8. A lasting machine, having in combination, pincers, a rotatable wiper for creasing the upper into the angle between the feather- 130

edge and lip of the sole, operating mechanism for the pincers, connected devices for adjusting the wiper to and from operative position and for causing the pincers to plait the upper upon adjustment of the wiper into operative position and mechanism for continuously rotating the wiper while it is in operative position.

9. In a lasting machine, in combination, means for stretching the upper, mechanism for supplying binding material, a presser constantly in engagement with the upper to place said material in binding relation with the overworked upper and mechanism for imparting continuous uninterrupted operative movement to said presser.

10. A lasting machine having in combination, means for stretching the upper, a main shaft, connections therefrom with the upper stretching means for operating said means, a rotatable wiper for creasing the upper into the angle of union between the feather-edge and lip of the sole and connections between said wiper and said shaft for causing 25 said wiper to be continuously rotated upon rotation of said shaft.

11. In a lasting machine the combination with lasting devices, of a rotatable member arranged to crease the upper into the angle 30 between the feather-edge and lip of the inner sole and to place a binder in place for securing the upper in lasted position and means for effecting continuous uninterrupted rotation of said member.

35 12. In a lasting machine, a rotatable wiper provided with peripheral fingers for creasing the overlasted margin of upper into the angle of union between the feather-edge and lip of the sole and means for effecting continuous uninterrupted rotation of 40 said wiper.

13. In a lasting machine, lasting devices, a rotatable wiper and means for effecting continuous uninterrupted rotation of said 45 wiper about an axis substantially perpendicular to the shoe bottom.

14. A lasting machine having in combination, pincers, operating mechanism for causing the pincers to seize, pull and lay 50 down the edge of the upper upon the shoe bottom, and means continuously and uninterruptedly moving in engagement with the upper to press the upper toward lasted position before the pincers seize it.

55 15. A lasting machine having, in combination, pincers, operating mechanism for causing the pincers to seize, pull and lay down the edge of the upper upon the shoe bottom, a wiper, and means for rotating the 60 wiper to press a portion of the upper toward lasted position in advance of the operation of the pincers upon that portion of the upper.

16. A lasting machine having, in combination, pincers, operating mechanism for

causing the pincers to seize, pull and lay down the edge of the upper upon the shoe bottom, and means constantly in engagement with the upper and moving continuously during the interval between the release of one portion of the upper by the pincers and the seizure of a fresh portion to prepare the said fresh portion for the action of the grippers upon it.

17. A lasting machine having, in combination, pincers, operating mechanism for causing the pincers to seize, pull and lay down the edge of the upper upon the shoe bottom, and means constantly in engagement with the upper and moving continuously during the interval between the release of one portion of the upper by the pincers and the seizure of a fresh portion to rub down the lasted portion of the upper.

18. A lasting machine having, in combination, pincers, operating mechanism for causing the pincers to seize, pull and lay down the edge of the upper upon the shoe bottom, and means constantly in engagement with the upper and moving continuously during the interval between the release of one portion of the upper by the pincers and the seizure of a fresh portion to gather the fresh portion of the upper inwardly toward lasted position and to rub 90 down and compact upon the shoe bottom the portion released by the pincers.

19. A lasting machine having, in combination, pincers, mechanism for causing the pincers to seize, pull and lay down the edge 100 of the upper upon the shoe bottom, and supplemental lasting means continuously and uninterruptedly moving in operative engagement with the upper during the entire interval between the release of one portion 105 of the upper by the pincers and the seizure of another portion.

20. A lasting machine having, in combination, pincers, operating mechanism for causing the pincers to seize, pull and lay 110 down the edge of the upper upon the shoe bottom, and a wiper continuously and uninterruptedly driven in contact with the upper upon the shoe bottom during the interval between the release of one portion of 115 the upper by the pincers and the seizure of a fresh portion.

21. A lasting machine having, in combination, pincers, operating mechanism for causing the pincers to seize, pull and lay 120 down the edge of the upper upon the shoe bottom, and means shaped to overlie and press inwardly and downwardly a toe binding wire and continuously driven in contact with the toe binding wire during the entire 125 interval between the release of one portion of the upper by the pincers and the seizure of a fresh portion to bind the wire down into the angle between the feather and lip of the shoe inner sole.

22. A lasting machine having, in combination with lasting instrumentalities, a rotatable wiper having its edge scalloped to form peripheral projections, and means for continuously operating the wiper to cause the said projections to act by impact to drive the upper against the lip or shoulder of the innersole and set it in lasted position by rapidly repeated blows directed horizontally against the stock.

23. A lasting machine having, in combination, pincers, a rotatable wiper having its edge scalloped to form peripheral projections, operating mechanism for causing the pincers to move laterally in the direction

to carry the upper under the wiper into the angle between the wiper and the body of the shoe while the wiper is turning, and means for continuously rotating the wiper to cause the said projections to bite the upper and set it in lasted position by rapidly repeated blows of gradually increasing closeness of contact.

In testimony whereof I have signed my name to this specification in the presence of two subscribing witnesses.

THOMAS H. McAULIFFE.
